COVER OR CLOSURE MEANS FOR LIFTABLE
AND LOWERABLE IMMERSION BATHS

Albert Boecler, Berlin, and Kurt Bratring, Dahlem, Berlin, Germany, assignors, by mesne assignments, to Neocell Products Corporation, a corporation of Delaware

Application July 9, 1938, Serial No. 218,324

6 Claims. (Cl. 18—24)

This invention relates to covers or closure means for liftable and lowerable immersion tanks, vessels or baths and is of great utility for producing articles from dissolved plastic substances by immersion. It has for its object to improve generally on closure means of this kind so as to permit of compact construction of the immersion apparatus and to obtain effective sealing of the immersion bath, or the compartment in which the bath is normally situated, with a view to preventing evaporation.

It has already been proposed to furnish the immersion bath, which may be moved into and out of the apparatus, with a folding or hinged cover which, when the bath is lifted, is opened by suitable stops provided at the point of normal location of the bath.

A first disadvantage in the known arrangement lies in the fact that to allow for the rocking movement of the cover, which may consist of one or of two parts, the bath requires to be lifted a considerable distance, that is to say, a large space must be provided between the bath and the mould to be immersed therein. The immersion apparatus is governed in its size by this fact alone, and on this account the immersion chamber must be made unduly large. A further disadvantage of this type of apparatus, in which the cover is mounted on the bath or on the wall of the compartment in which the bath is situated, consists in the fact that the cover engages only loosely with the associated closure means, so that its closing movement is not a positive one, but takes place only as a result of the weight of the cover. In consequence the closing of these loosely moved covers is very unsatisfactory, and a gastight closure of the bath or its associated compartment cannot be obtained. On lack of a proper closure of the cover a skin is formed on the dissolved plastic substance in the bath which may give rise to defects in the articles produced upon the subsequent immersion.

According to the invention, the drawbacks referred to are overcome by guiding the cover for the immersion bath or its compartment in positive fashion both in the opening as well as in the closing, and making the cover of two parts, which are moved apart laterally, so that this cover does not call for any appreciable amount of space above it. Owing to the fact that the two parts of the cover are moved apart laterally the extent of movement of the immersion bath, and consequently the height of the immersion apparatus, can be reduced to a minimum, whilst in consequence of the positive guiding

the two parts of the cover, which can be furnished with suitably fitting faces, are made to bear tightly one against the other and against the wall of the bath or the wall of the chamber containing it. The lifting means for the bath, for example a hydraulic plunger which in accordance with the invention is required to perform only a comparatively small lifting movement, is caused to engage during its initial movement prior to the actual lifting of the bath with a rocking lever system, which during this short movement, i. e., prior to the lifting of the bath, causes the two-part cover to be opened, whilst upon the subsequent lowering of the bath after the immersion, when the bath has again been deposited in its initial position and the movement of the lifting device is about to terminate the same lever system causes the cover portions to be applied tightly to the now stationary bath.

The invention is illustrated by way of example in the accompanying drawings, in which

Fig. 1 is a section through the chamber adapted to receive the immersion bath, showing a hydraulic plunger mechanism engaging with a rocking lever system for actuation of a positively guided two-part cover.

Fig. 2 illustrates diagrammatically a complete immersion apparatus broken away at the bottom to show the position of the bath when it is about to be lifted, with the two-part cover opened laterally.

In Figs. 1 and 2 the bath 1 is shown mounted by means of brackets 3 on rolls 4 adapted to run on rails 5, which are disposed transversely through the apparatus and on which the bath 1 can be moved through a suitable opening into and out of the apparatus. Between the rails 5 is a hydraulic plunger 7, which in the retracted position in Fig. 1 enables the bath to be moved into the apparatus without obstruction, but in the position shown in Fig. 2, namely the position preparatory to the actual lifting of the bath, bears against the bottom of the latter. The plunger 7 moves in the cylinder or guide 2. On the plunger 7 there are provided two angle plates 3, 8, which engage by means of studs 9 in a rocking lever system.

In operation the bath 1 is introduced into a chamber having heat-insulated walls 10, 10. To the right and the left of this chamber there are rotatably mounted at a low point shafts 11, 11, on which are rigidly mounted rocking levers 12, 12. These rocking levers extend over the wall of the chamber 10 and are respectively

pivoted at 14 to the two halves 13 of the two-part cover for the bath.

At their opposite ends, i. e., at their contacting edges, the two halves 13 of the two-part cover are suspended by means of lugs 15, 15 and studs 16, 16 in a slideway 17. This slideway may consist of a member having a U-shaped section in which the studs 16 are guided on either side.

In a preferred embodiment there are provided two rocking levers 12 on each of the shafts 11, one at the front and the other at the rear of the apparatus, in order to preclude any tilting tendency on the part of the two halves of the cover either during their movement or upon the closing action. Similarly, to ensure proper guiding, slideways 17 with the cooperating studs can be provided in the plane in front of the bath and behind it.

On the rotary shafts 11 there are also rigidly mounted bifurcated rocking levers 18, the tines or branches of which are of unequal length. These levers 18 are engaged during a certain phase of the operation by the studs 9, attached as above stated to the plunger 7. Thus each lever 12, its shaft 11 and bifurcated lever 18, forms a unitary rigid rocker arm, which may, if desired, be a single casting or forging.

To permit of a tight fitting of the two halves of the cover 13 along their contacting edges the latter are preferably furnished with rubber gaskets or the like 19. A similar gasket 20 is also provided along the upper edge of the bath 1 with a view to precluding all possibility of evaporation in the closed position of the cover. These gaskets become noticeably deformed when the two halves of the cover are pressed tightly together and onto the bath.

When the vessel 1 has been introduced into the apparatus and stands (Fig. 1) in position to be raised by the lifting plunger 7 the studs 9, are in engagement with the bifurcated ends of the levers 18 and hold the latter in the horizontal position. In this manner, assisted by the weight of the plunger 7 in rigid connection with the studs 9, the two halves of the cover 13 are pressed tightly together along their inner edges 19 by way of the rocking levers 12, and since the latter have already passed their highest points with relation to the pivot shafts 11 the cover is pressed firmly on to the bath.

Upon the commencement of the lifting movement out of the position in Fig. 1 through the position shown in Fig. 2 up to the point of immersion of the moulds (not shown) the studs 9, since they are connected to the plunger 7, are also lifted. During the initial movement out of the position in Fig. 1 into that in Fig. 2, i. e., up to the point when the plunger 7 reaches the floor of the bath 1, the studs 9 are in engagement with the shorter branches of the bifurcated ends of the levers 18 and cause the latter to be rocked. This rocking movement is communicated to the shafts 11, on which the levers 18 are rigidly mounted, and through them in turn to the levers 12 mounted on either side of the bath 1, causing the levers 12 to be moved outwards. As a result of this movement the two halves of the cover 13 are slightly lifted at the points where they are pivoted to the levers 12, and are moved apart laterally. The studs 16 move along the slideway 17, thus guiding the inner edges of the cover halves 13 in slightly lifted position above the edge of the bath. At the moment when, as shown in Fig. 2, the plunger 7

reaches the floor of the bath 1 the studs 9 are in position to disengage from the short branches of the levers 18, and the rocking movement ceases. The two halves of the cover 13 remain in the position shown in Fig. 2 until, following completion of the immersion process, the bath 1 is again lowered by the plunger 7. At the moment when the rolls 4 on the vessel 1 are deposited on the rails 5 the studs 9 move into engagement with the long branches of the bifurcated ends of the levers 18, and as the plunger 7 continues to move downwards and away from the bottom of the bath, the levers 12 are rocked inwards and the studs 16 move along the slideway 17 and the cover 13 is moved positively into the closed position. In the extreme position of the plunger 7 the weight of the latter causes the cover portions to be pressed firmly together and against the edge of the bath.

The closure of the bath 1 by the cover gaskets 20 is normally substantially perfect. However, as insurance against possible leaks around the edges of the bath we have provided an additional seal between the walls 10 of the immersion chamber and the outer edges of the covers. Referring to Fig. 1, 21 are rubber strips attached to the sides 10 of the chamber near the top and extending somewhat thereabove. 22 are extensions from the covers 13 which, when the covers are closed, engage with the rubber gaskets 21, bending them over into the positions shown, and thus forming an air-tight seal between the immersion chamber and the remainder of the apparatus. The members 22 may conveniently be formed of sheet metal, for example spring steel, bent into the form shown in Fig. 1. They are attached to the outward ends of the covers 13 in any convenient manner.

What we claim as new and desire to secure by Letters Patent is:

1. In apparatus for the production of articles of plastic composition by immersion of molds in a bath, the combination which comprises a vertically movable tank, a tightly fitting cover for said tank, a substantially horizontal guideway for said cover, a rocker arm pivotally attached to said cover, disposed to withdraw said cover laterally along said guideway when rocked, and arranged to be actuated by engagement of a member therewith, and means for lifting said tank vertically, said means being provided with a member disposed to engage and actuate said rocker arm.

2. In apparatus for the production of articles of plastic composition by immersion of molds in a bath, the combination which comprises a supporting frame a vertically movable tank, means for lifting and lowering said tank, a two-part cover adapted to fit the top of said tank, a lever system cooperatively associated with each side of said tank, each of said lever systems comprising an angle member pivotally mounted at its angle on said frame and having a longer arm pivoted at its end to the outer end of one part of said cover and a bifurcated shorter arm, a guideway adjacent to said cover, means on the outer end of said one part of said cover engaging said guideway to guide said cover in a prescribed laterally directed path, a stud on said lifting and lowering means adapted to engage the bifurcation of said shorter arm to rock said lever about said support and laterally remove said part of said cover upon the initial upward movement of said lifting and lowering means, to be disengaged from said bifur-

cation during the remainder of said upward movement and the initial downward movement, and to reengage said bifurcation during the final downward movement of said lifting and lowering means, to move the two parts of said cover laterally together and onto the top of said tank.

3. In apparatus for the production of articles of plastic composition by immersion of molds in a bath, the combination which comprises a vertically movable tank, a massive member arranged to be movable upward and downward for lifting and lowering said tank, cover means for said tank, elastic gaskets on each part of said cover at points of contact with the other part of said cover and at points of contact with said tank, and rocker arms arranged to be actuated by movement of said massive member for laterally removing said cover upon initial upward movement of said massive member and for replacing said cover and pressing said cover tightly into position upon final downward movement of said massive member.

4. In apparatus for the production of articles of plastic composition by immersion of molds in a bath, the combination which comprises a vertically movable tank, means for lifting said tank, a tightly fitting cover for said tank, guiding means constraining motions of said cover substantially to the horizontal, a rocker-arm pivotally attached to said cover and arranged to withdraw said cover within the constraints of said guiding means when rocked, said rocker-arm having a portion disposed in the path of travel of said tank-lifting means and engageable by said tank-lifting means throughout the initial stage of travel of said tank-lifting means, whereby movement of said tank-lifting means produces at first lateral withdrawal of said covers and then vertical movement of said tank.

5. In apparatus for the production of articles of plastic composition by immersion of molds in a

- bath, the combination which comprises a supporting frame, a tank, a laterally removable cover for said tank, a massive member arranged to be movable upward and downward within said frame for lifting and lowering said tank, a rocker-arm pivotally attached to said frame and to said cover and having a portion lying in the path of travel of said massive lifting member and arranged to be actuated thereby, said rocker-arm being disposed to support at least a part of the weight of said tank-lifting member when the latter is in its lowermost position and to translate said weight into a force tightly closing said cover.
6. In apparatus for the production of articles of plastic composition by immersion of molds in a bath, the combination which comprises a supporting frame, a tank, vertically movable means for lifting and lowering said tank within said frame, a cover for said tank provided with elastic gaskets at points of contact between said cover and said tank, a lever system cooperatively associated with said tank, said lever system comprising an angle member pivotally mounted at its angle on said frame and having one arm pivotally attached to said cover and another arm extending within said frame into the path of movement of said tank-lifting means, means connected with said lifting means adapted to engage said other arm to rock said lever about said frame and laterally remove the cover from the tank upon initial upward movement of the tank-lifting means, to be disengaged from said other arm during the remainder of said upward movement and the initial downward movement, and to reengage said other arm to move said cover laterally over said tank and press it tightly into position during the final downward movement of said tank-lifting means.
